(57) **CLAIM**

The ornamental design for a display screen or portion thereof with animated graphical user interface, as shown and described.

DESCRIPTION

FIG. 1 is a first image of a display screen or portion thereof with animated graphical user interface showing our new design;

FIG. 2 is a second image thereof;

FIG. 3 is a third image thereof;

FIG. 4 is a fourth image thereof;

FIG. 5 is a fifth image thereof; and,

FIG. 6 is a sixth image thereof.

The outermost broken line represents a display screen or portion thereof and forms no part of the claimed design. The remaining broken lines in the drawings illustrate portions of the graphical user interface that form no part of the claimed design.

The appearance of the animated user interface sequentially transitions between the images shown in FIGS. 1 through 6. The process or period in which one image transitions to another forms no part of the claimed design.

The grayscale tones used to depict the animated graphical user interface in the drawings are intended to represent a contrast in appearance.
